UNITED STATES PATENT OFFICE.

CARL O. LINN, OF BRIDGEPORT, KANSAS.

MANURE-LOADER.

No. 888,916.

Specification of Letters Patent.

Patented May 26, 1908.

Application filed March 11, 1908. Serial No. 420,356.

To all whom it may concern:

Be it known that I, CARL O. LINN, a citizen of the United States, residing at Bridgeport, in the county of Saline and State of Kansas, have invented a new and useful Manure-Loader; and I do hereby declare the following to be a full, clear, and exact description of the invention, such as will enable others skilled in the art to which it appertains to make and use the same.

My invention relates to improvements in manure loaders.

It has for its object primarily to provide for the ready removal or taking up of the manure from the ground and lifting it to an elevation for its convenient delivery or loading into a wagon or other suitable means for the spreading thereof where desired as in applying it for fertilizing purposes.

Further objects of the invention are to carry out the aforesaid ends in a simple, expeditious and effective manner, as well as to promote facility of the operation of the machine.

Additional advantages and objects of the invention will appear as the nature thereof is more fully disclosed from the subjoined description and accompanying illustration, wherein,

Figure 1 is a side elevation partly in section of my invention in the preferred form of its disclosure. Fig. 2 is a plan view of the same, certain portions being broken away. Fig. 3 is a vertical section thereof, produced just in rear of the axle of the forward transporting wheels, viewing rearwardly. Fig. 4 is an enlarged detail view, showing more especially the fork-holder or head and connections between the same and the fork, viewing said parts in rear elevation. Fig. 5 is also a detailed view disclosing more especially the flat-metal fork holder of general triangular outline and adjunctive parts for effecting connection therebetween and the fork.

In the preferred embodiment of my invention, I employ a suitable carrying frame 1 for the operative parts thereof, mounting it upon transporting wheels 2, through their axle 3, and a steering or guiding wheel 4 through its spindle 5, having a tiller 6, said frame also having fixed thereto at one end an upright frame 7, suitably braced in position by means of lateral oblique bars or braces 8, 9, suitably secured to the upright and lateral members of the aforesaid frame.

A fork 10, having its tines preferably of the outline or construction shown has its head end formed of a rod 11, axially or pivotally supported in lateral bars or arms 12, at their outer or forward ends, the inner ends of the latter having pivotal connection with the upper ends of the lateral bars of the upright frame 7, which first noted bars or arms are suitably held or braced in parallel alignment by diagonally crossing rods or braces 13 secured at their ends to said arms, near the outer ends of the latter, and to said frame bars, respectively at their upper ends.

A flat-metal connection or plate 14 of general triangular or approximately quadrant outline has its apex provided with an aperture 14^a and the rod or axis 11 of the fork 10 passing through said aperture thus effecting connection between said fork and said plate or holder, as shown, said plate or holder standing edgewise to said fork. Said plate or holder has also an arcuate slot 14^b conforming to its enlarged rounded end and through this slot, passes a cross pin 15 effecting connection between parallel bars 16 between which said plate 14 is arranged to have movement and which cross pin is effective to engage additional parallel bars 17 having suitably fixed connection as at 17^a with the lower rear corner-edge of said plate or cam 14. Said bars 16 have pivotal connection at their rear ends by means of a cross pin 16^a with upstanding bars 18 connected at their lower ends to the upper cross piece of the upright frame 7 and to which they are suitably braced as at 19. A metal keeper or guard 20 is fixed to the forward edges of the bars 17 and serves to guide or control the cross pin-equipped ends of the arms or bars 16 and hold the bars 17 in effective position, as in actuating the rake holder or cam 14 as will be readily understood.

A suitable cable or connection 21 for the retention of the fork in effective working position, secured at one end of the fork as clearly shown in Fig. 1, and suitably guided and passed over pulleys 22, 23 carried by the bars 17, 16 respectively, is connected to, and adapted to be controlled by a hand-wheel equipped arm 24 suitably journaled in position, the function of which arrangement of parts will presently appear. A hand-wheel equipped shaft 25, also suitably journaled in position, has its forward end provided with a gear wheel or pinion 26 meshing with a pin-

ion 27 carried by a shaft 28 suitably journaled in the frame 7, also having an additional pinion or gear-wheel 29 at the opposite side of the machine, geared to a much larger gear-wheel 30 secured upon a shaft 31 also journaled in the frame 7. The shaft 31 is also provided with a second pinion 32 and with this pinion is engaged the rack or cogged surface 33^a of the fork-lifting bar 33 with its forward end engaging the fork 10, said bar being suitably supported in position within a roll-equipped keeper or guide 34. Said guide or keeper has branching or extending therefrom arms 35 connecting with the rod 15 or part 11 of the fork, for firmly bracing said guide in place.

A rod 36, connected to the regulating bars 16, at their upper ends, has its inner end pivoted to a bar or member 37, having screw-threaded connection with a hand-wheel 20 equipped screw 38 supported for rotation without endwise movement in a standard or support 39 secured upon the frame 1, and by the suitable actuation of which the bar rod 36, together with the bars 16, may be moved forwardly, or rearwardly accordingly providing for turning the fork-tines downwardly or upwardly as in leveling the same, as will be readily understood.

In order to operate the fork for taking up the manure and elevating it and for dumping the fork-contents as into a wagon for suitably spreading the manure or fork-contents, the hand-wheel of the rod or shaft 25 is suitably actuated by hand, which will have the effect, through the gearing operated therefrom, to exert a pushing action upon the fork through the member 33 which will cause the fork to move upwardly, the member 12 giving the upward tendency to the movement, and controlling the same until the fork has been lifted to the desired altitude. When in the latter noted position, the fork may be relieved of its contents by releasing the cable-winding drum 24, allowing the cable 21 to suitably unwind and the dumping bar 17 to move upwardly, causing the fork 10 and holder or cam 14 to turn upon the rod axis member 11, accordingly resulting in the dumping of the fork-contents.

This machine is characterized for its simplicity, fewness of part, facility of actuation and effectiveness for its intended purpose as herein described.

It will be understood that I do not limit myself to details as to form, arrangement or construction of the above disclosed parts, the scope of the invention being defined by the subjoined claims.

1. A machine of the class described, comprising a fork member, a holder or cam having pivotal or axial connection with said fork member means for elevating said fork, upstanding bar-members having fixed connection with said holder or cam, regulating

means having movable connection with said fork holder or cam, and adapted to engage said fixed upstanding bar members for elevating and dumping said rake.

2. A machine of the character described, 70 embracing a fork a holder or cam therefor, and having pivotal connection with said fork, means for elevating said fork, upstanding bar members having fixed connection with said fork-holder or cam, regulating means 75 having movable connection with said fork holder or cam and adapted to engage said upstanding bar-members and means for regulating or controlling the movement of said fork as it is elevated for dumping action. 80

3. A machine of the class described, comprising a fork a holder or cam therefor having pivotal connection with said fork, means for elevating said fork, upstanding bar-members fixed to said fork-holder, regulating means 85 having movable connection with said fork-holder, and having engagement with said fixed upstanding bar-members, and means for releasing same when elevated.

4. A machine of the character described, 90 comprising a fork, a holder or cam of substantially quadrant-outline, having pivotal connection with said fork, means for elevating said fork, upstanding bar-members fixed to said fork-holder and regulating means hav- 95 ing movable connection with said fork holder and adapted to engage said upstanding bar-members.

5. A machine of the class described, comprising a fork, a holder or cam pivoted to said fork, of substantially quadrant outline and having a curved slot conforming to its enlarged end, upstanding bar members fixed to said fork, holder or cam, means for elevating said fork, and regulating means having cross- 100 pin connection with said fork holder, extending through said slot and adapted to engage said upstanding bar-members. 105

6. A machine of the character described, comprising a fork a holder or cam of substan- 110 tially quadrant outline with its apex pivotally connected to said fork, said holder or cam having a curved slot conforming to its enlarged end portion, upstanding bar-members fixed to said holder or cam at its lower 115 inner corner edge, regulating means having cross pin connection with said cam or holder, passing through said slot, means connected to said fork holder or cam, for prescribing the movement of the fork, lifting means for said fork and means for actuating said lifting means. 120

7. A machine of the character described comprising a fork, a holder therefor of sub- 125 stantially quadrant-outline, with its apex pivotally connected to said fork, and having a curved slot upstanding bar-members fixed to said fork holder and having fixed thereto a keeper or guard regulating means equipped with a cross pin between its members, adapt- 130

ed to engage said upstanding bar-members and to pass through said slot, said cross pin also passing through said keeper or guard, means pivoted to said fork-holder for giving 5 an upward direction to the movement of said fork and lifting means for said fork.

8. A machine of the character described, comprising a fork a holder for said fork, pivoted thereto, upstanding bar-members fixed 10 to said holder, means connected to said holder for giving an upward direction to the movement of said fork, regulating means having its connected members receiving between them, said holder, said members having 15 connecting means passing through a curved slot in said holder, and engaging said upstanding bar-members, means for the retention of the fork in effective position a lifting bar effective for engaging said fork, having 20 a cogged surface, or rack thereon, a manually actuated shaft, and gearing between said

shaft and said lifting bar for the actuation of the latter by said shaft.

9. A machine of the class described, comprising a fork, a pivoted holder or cam for 25 said fork, upstanding bar members fixed to said fork-holder, regulating means having movable connection with said fork-holder and adapted to engage said upstanding bar members, means for leveling the position of said fork embracing rod-connection with said regulating means manually actuated screw-threaded means for said rod-connection, lifting means for said fork, and means for actuating said lifting means. 30

In testimony whereof I have signed my name to this specification in the presence of two subscribing witnesses.
